DESIGN FOR A CARPET.

SPECIFICATION forming part of Design No. 15,405, dated September 16, 1884.

Application filed August 6, 1884. Term of patent 3½ years.

To all whom it may concern:

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The design consists of a system of lichen or 15 moss-like figures running irregularly over the face of the design, and filling it with moss sprays having irregular but continuous stem-connections.

I claim—

The design for a carpet, consisting of the connected moss-like sprays, substantially as shown and described.

JAS. L. FOLSOM.
